UNITED STATES PATENT OFFICE.

JAMES B. RIVERA, OF BALTIMORE, MARYLAND.

CONFECTION-GRINDING APPARATUS.

SPECIFICATION forming part of Letters Patent No. 289,860, dated November 20, 1883.

Application filed May 3, 1883. (No model.)

To all whom it may concern:

Be it known that I, JAMES BARRERA RIVERA, a citizen of the United States, residing at Baltimore, in the county of Baltimore and State of Maryland, have invented certain new and useful Improvements in Confection-Grinding Apparatus, of which the following is a specification.

My invention relates to an apparatus adapted to be used by confectioners for grating, grinding, and reducing to a pasty substance the kernels of almonds, cocoa, cocoanuts, and the meats or nutritious parts of other fruits, and adapting them for use as ingredients of confections and other analogous articles; and my invention consists in certain features of construction, combinations of parts, and arrangements of rolls driven at relatively different speeds, as hereinafter described, and specifically set forth in the claims.

Referring to the accompanying drawings, forming a part hereof, Figure 1 is a central vertical section of an apparatus constructed for the aforesaid purpose and in accordance with my invention. Fig. 2 is a front elevation of the same, partly in section, and with the roller-scrapers removed. Fig. 3 is a side elevation, showing the arrangement of the train of operating-gears; and Fig. 4 a section on a larger scale, showing details of construction.

Like letters indicate like parts in all the figures.

A represents a hopper supported in a frame, A', secured by means of swivel-bolts *a* upon a frame-work, A², which is secured to a box or trough, A³, as clearly shown. In the hopper-bottom are two feed-rolls B and C, having their peripheries provided with diamond-shaped projections by means of longitudinal and circumferential grooves cut thereon. These rolls are arranged to form an inclined plane, and in such relation to the bottom and end walls of the hopper that substances placed therein are by gravity fed toward the roll revolving at the highest speed, and thus made to enter between said rolls, even when using such substances as cocoanut in large fragments. The rolls B and C are mounted on shafts B' C', mounted in the frame A', and provided with gears B² C², respectively, at opposite sides of

the machine. In the frame A² are supported the rolls D, E, and F, the rolls D and E being arranged in a nearly horizontal plane, and the roll F in a vertical plane passing between the rolls D and E; and these rolls D, E, and F are journaled in adjustable bearings *d*, *d'*, and *f*, in order that they may be adjusted—the former toward the roll E and the latter toward the roll D—by means of the eccentric lever *f'* and regulating-screw *f''*. A suitable doctor or scraper, G, is secured adjustably in proximity to each of the rolls. The rolls B and C are ridged, toothed, or provided with diamond-shaped projections, in order to act as graters or disintegrators, and by a suitable train of gearing, hereinafter described, are driven at speeds differing in each. The relative rotation of each roll in the entire apparatus is by said train of gearing caused to differ from all the others—that is to say, I prefer (but do not limit myself to any exact difference in the relative speeds of rotation of the rolls) that the roll B shall rotate about six times as fast as roll C, roll D about twice as fast as roll E, and roll F about five times as fast as roll D, while the relative speeds of rolls B and C to that of rolls D, E, and F are governed in their relative rapidity in accordance with the amount of the product passing therefrom to the rolls D, E, and this amount should not be in excess of that which the latter can properly treat, as hereinafter described. Each pair of rolls is rotated in such direction as will feed material down through or between them. Material placed in the hopper rides over the roll C and strikes the roll B, the rotation of which, being faster, and at its upper portion, toward the roll C, acts to draw the material down between them, and in passing through it is broken and bruised or comminuted into fine pieces; and in materials of the character above mentioned, adhering particles which fall upon the relatively slower roll E and come into contact with its faster companion D are again ground into a thin sheet, which is carried between the roll D and its faster companion F, where a further division of the sheet is accomplished, and it is finally arrested by the last scraper and falls within the box A³.

By means of the swinging bolts *a*, pivoted

at a^2 to the main frame, and provided with thumb-nuts a^3 , the hopper and its rolls B C may be removed (by first swinging the bolts and nuts off the top of frame A') and thoroughly cleaned, and the crushed material may then be subjected to repeated treatments of or by the rolls D E F, each treatment increasing the fineness of texture and homogeneity.

H H represent gages or chutes located over and between the rolls D E, for the purpose of preventing the spreading of the material beyond the ends of the rolls, and by means of rods or screws h, attached thereto, each gage is rendered adjustable, in order to determine the width of the sheet to be formed by the rolls.

Although I have shown one train of gearing, I do not wish to be limited to its exact arrangement, but deem any arrangement within the skill of a competent mechanic as a matter of choice. In this instance the shaft E' of roll E is made the power-shaft, and by means of a gear, E², thereon drives a pinion, B², of the shaft E' of roll B. Upon the opposite end of the shaft E' is another gear, E³, which meshes with a gear, D², on the shaft D' of the roll D. On the same shaft, and inside of gear D², is a gear, D³, which drives a pinion, F², on the shaft F' of roll F. These gears are of relative sizes to produce the desired relative speeds of rotation of the rolls, as described. The roll D may be chambered and provided with a hollow shaft to receive steam and keep

it, as well as the adjacent rolls, at a proper degree of heat. By the above-described arrangement of rolls the passage of material through them and its condition can be easily seen and followed by the attendant, and all clogging or imperfect grinding be prevented.

Having described my invention and its operation, what I claim as new is—

1. The combination of the hopper A, the corrugated feed or grating rolls B C, arranged at an incline within the delivery-opening of said hopper, frame A', the smooth rolls D, E, and F, a separate frame, A², therefor, and means for removably securing said frames together, substantially as and for the purpose described.

2. The combination of the frame A², the frame A', provided with the hopper A, and the feed or grating rolls B C, arranged at an incline within the delivery-opening of said hopper, with the smooth rolls D and E, arranged in nearly the same horizontal plane, the roll F, below and between the rolls D and E, and means for rotating each of said rolls at a different speed from that of the others, substantially as specified.

In testimony whereof I affix my signature in presence of two witnesses.

JAMES BARRERA RIVERA.
